United States Patent Office.

MARTIN WINGER, OF EPHRATA, PENNSYLVANIA.

Letters Patent No. 71,935, dated December 10, 1867.

IMPROVED CIDER-MILL AND PRESS.

The Schedule referred to in these Letters Patent and making part of the same.

TO ALL WHOM IT MAY CONCERN:

Be it known that I, MARTIN WINGER, of Ephrata, Lancaster county, in the State of Pennsylvania, have invented a new Improved Combined Apple-Mill and Cider-Press; and I do hereby declare that the following is a full, clear, and exact description of the construction and operation of the same, reference being had to the accompanying drawings, making a part of this specification, in which—

Figure 1 is a perspective view of the mill and press complete.

Figure 2, a plan view of the supporting-frame, grooved bed, &c.

Figure 3, a cross-section through the mill.

Figures 4, 5, and 6, detached portions of the same.

Figure 7 shows pulley-wheels on the bottom Q.

The nature of my invention is in providing a series of perforated boxes, with a hinged bottom, supported on rollers over a grooved bed. These boxes, say fifteen in number, (be they more or less,) form the outer circumference of a wheel, with a flange provided with cogs, and the pressing performed by an inclined plane (spirally) over the boxes, which are revolved, filled, pressed, and their contents discharged automatically each revolution, in combination with a stationary mill, for grinding the apples or substance to be subjected to pressure. Springs or weights may be used on the inclined plane.

To enable others skilled in the art to make and use my invention, I will proceed to describe its construction and operation.

The framework consists of four corner-posts, A, with cross-pieces from each centrally and at top B B'. The top corners have braces, Z. These corner-braces form the top into an octagon over the circular press-boxes D, for the support of the continuous or hinged inclined plane H, being slotted in the centre of each of the eight sides, for the reception of the plate I, connected with the inclined plane H, as shown. Springs or a weighted lever may be applied, to give the inclined plane a graduated resisting or pressing power; connected with the supporting-plate I. There is also a central cross-piece or bearing, M, above, and one below, O, for a step, which between them support a vertical shaft, L, connected with four arms, N, these latter being connected to the inner side of the boxes D, constituting them a wheel moving horizontally on said shaft L. The outer side of said circle of boxes D has a continuous flange with cogs around the entire circumference, (whether cast in segments or otherwise to form the boxes.) This wheel or series of press-boxes is revolved by a pinion, S, on a vertical shaft, T. This shaft has a cogged wheel, Y, above, and receives motion from a screw, on the outer end of a shaft, which is driven by a strap-pulley on its opposite end, outside the hopper or mill X. On the inside of the mill is a grinding or toothed roller. There are two grinding, V, and one, W, crushing-roller, and a spout that empties into the revolving press-boxes. (An endless apron may be employed.) But as I claim no novelty in the crushers or gearing, I do not confine myself to any specific arrangement, but the drawings indicate my mode of grinding and emptying the pulp into the boxes.

The movement of the mill revolves my press-boxes. These boxes D have a loose bottom, Q, hinged at one end. These are held in place by a series of rollers, P, over a circular groove in the bed-plate C. At a point of the circular groove near the hopper or mill, an open space is left, from which point, on both sides, the groove deepens towards the spout, where the juice or cider is discharged into a vessel, as shown, fig. 1, at the open space in the bed-plate C. The bottom being unsupported and the pressure completed, the hinged-bottom drops down and empties the pomace. When emptied, the rollers P again press the bottom to its place, ready for being filled, each in its order, as revolved in the common wheel-like form.

These boxes are perforated on two sides, through which the pressed cider or juice finds its way into the channel of the bed-plate C. On each partition, between the boxes D, there is a central upright, F. The press-block K fits into the chamber or box, having a notch, k, also a central upright, E, with a side or terminal grooved pulley, G, and cross or side-arms e, which, as also the notch k in the press-block K, are guided in their up-and-down motion by the uprights F aforesaid. The grooved pulley G, on each piston or pressing-arm E, with its press-block or lid K, comes in contact with the inclined plane H suspended over the circle of boxes, so that, when the box is filled, the lid K is on top of the box. At this point the inclined plane is sufficiently elevated, but, as the boxes in order move onward, and the inclined plane narrows down, the grooved pulleys necessarily

are lowered, or, in other words, the lid K is pressed down lower and lower, as it passes on, and by the time the circle (as well as the pressure) is completed, the inclined plane suddenly terminates, the bottom drops, the pulp is emptied, and the press-block K drops down, and, being carried forward, the pulley comes on top of the suddenly inclined way R, fig. 5. This carries the press-block K clearly upwards, out of the way of the spout, through which the now open box is filled. As it passes on it again arrives to the point of action of the inclined plane, as already stated; so on, in one continuous round. The apples can be fed into the hopper of the mill from a wagon, and by the time they are all shovelled in, the whole are converted into cider.

With this description and the drawings I think the whole matter is sufficiently clear. The braces or supports I of the inclined plane are notched at top. Fig. 4 shows a weight suspended to give any amount of resistance to the press-blocks. I find that by jointing the inclined plane in segments, it answers as well as a continuous one, when properly adjusted and weighted.

I have now a large press in operation; and complicated and expensive as it may seem, the satisfaction given by the ease, speed, and effective work, is such as to make it highly desirable in cider countries, and its utility will be equal to its novelty.

I am not aware that any press was ever constructed substantially in this manner, with revolving boxes, &c., for making cider or the like.

I would simply add that, instead of the series of rollers P, the bottom of each box could be provided with an axle and a pulley-wheel on each end, moving in a proper track to the opening in the same, through which the hinged bottom with the wheels would drop open to empty out, an inclined plane would return the bottom, as the wheels would again be raised on to the track. Fig. 7 shows such a bottom, which I deem equivalent to the fixed rollers P on the bed-plate C.

What I claim as my invention, and desire to secure by Letters Patent, is—

1. A series of press-boxes D, with perforated sides and an external cogged flange, d, all connected in the form of a wheel, revolving horizontally, with its cross-arms N secured centrally to a vertical shaft, L, in combination with the bearing M and step O, sustained on a framework, A B B', all arranged substantially in the manner and for the purpose specified.

2. With the revolving press-boxes D, I claim the press-block and central upright K E, pulley G, guides F, arms e, in combination with the inclined planes H and R, all arranged and operating substantially in the manner and for the purpose specified.

3. In combination with the revolving box-wheel D D N N and pressing arrangement, I also claim the hinged drop-bottom Q, in combination with a series of rollers or pulleys, P, or their equivalents, for the purpose and in the manner shown and described.

4. In combination with my horizontal box-wheel, I claim the arrangement of the gearing and mill-hopper X and crushers W V, pinions Y S on shaft T, all combined substantially in the manner specified.

5. In combination with an apple-mill, I claim a cider-press, with a series of presses in a horizontal revolving wheel, substantially as and for the purpose specified.

MARTIN WINGER.
